UNITED STATES PATENT OFFICE.

CHARLES SAMUEL BERRY, OF TUCKERMAN, ARKANSAS, ASSIGNOR OF ONE-THIRD TO
L. T. SLAYDEN AND ONE-THIRD TO J. S. GRAHAM, BOTH OF TUCKERMAN, ARKANSAS.

MENTHOLATED OR MINTED CATHARTIC SALTS.

1,212,888.

Specification of Letters Patent. Patented Jan. 16, 1917.

No Drawing.

Application filed July 5, 1916. Serial No. 107,690.

To all whom it may concern:

Be it known that I, CHARLES SAMUEL BERRY, a citizen of the United States, residing at Tuckerman, in the county of Jackson and State of Arkansas, have invented 5 certain new and useful Improvements in Mentholated or Minted Cathartic Salts; and I do hereby declare the following to be a full, clear, and exact description of the invention, such as will enable others skilled 10 in the art to which it appertains to make and use the same.

My invention relates to a pharmaceutical preparation and a special method of treatment of a medicinal agent whereby said 15 agent will be rendered much more efficient in character and my invention consists in a new and useful method or process and also in a new and useful product as will be hereinafter fully described and pointed 20 out in the claims.

The prime object of my invention among others is to disguise the normal taste and impart an agreeable odor or smell to salts 25 commonly employed as a cathartic, whereby by the salts treated by my method will be rendered pleasant in taste and smell or in other words rendered very pleasant and palatable, where without my treatment it would 30 be more or less disagreeable and nauseating in its effects, as for instance Epsom and other salts.

A further object of my invention is to utilize the salts, commonly employed as a 35 cathartic, as a vehicle to carry thoroughly incorporated with it an antiseptic and an anesthetic agent whereby the administration of the salts as a cathartic will also act beneficially upon the entire digestive tract.

Other objects and advantages will be hereinafter made apparent, reference being had 40 to the following detail statement.

A brief statement or formula of my invention is as follows: To 16 ounces of Epsom salts (magnesium sulfate) or other variety of cathartic salts I employ slightly more or less 8 grains of menthol crystals and also 8 drops of oil of peppermint and 45 8 drops of spearmint. Or in other words, the composition consists of equal parts of 50 menthol crystals, oil of peppermint; and oil of spearmint, to approximately one thousand parts of cathartic salts.

It is very important that the above shall 55 be thoroughly triturated in order to insure

the perfect incorporation of said parts with each other and I, therefore, first reduce the menthol crystals to a fine powder which is then thoroughly mixed with the salts, after which the mixture is preferably reduced to 60 a uniform powdered consistency as by grinding or by mortar and pestle.

It will, of course, be understood that the thorough commingling of the powdered menthol and salts may be accomplished in 65 any preferred manner deemed most effective for the purpose, the object being to produce an admixture of the character stated wherein the powdered menthol crystals will be most thoroughly incorporated 70 with the salts when the result will be found to be a most agreeable and palatable article, having not only the cathartic medicinal property of the salts but also a decided 75 antiseptic character which will also possess a sufficiently anesthetic and analgesic power to be of important and valuable service 80 in its action upon the nervous system and the intestinal tract, whereby cramped and spasmodic conditions are at once relieved with a resulting cure of flatulency, indigestion, sick and sour stomach, colic and the destruction of worms, etc.

I, therefore, desire to call particular attention to the fact that I have provided a 85 new and useful method of treating cathartic salts in such a manner that they will not only be rendered agreeable and pleasant to the patient but will also serve as a vehicle as stated for conveying an antiseptic and 90 pain relieving agency due to the thorough incorporation with the salts of powdered menthol crystals with oil of peppermint and spearmint substantially as hereinbefore specified.

It has been found in practice that mentholated cathartic salts will prove very efficacious for the treatment not only primarily of constipation but will also prove 100 a very agreeable cooling agent in its action on the stomach and bowels, but the salts will also be in its modified state, pleasant and palatable.

The administration or use of my mentholated salts will be substantially as follows; 105 i. e.: one to two tablespoonfuls in sufficient water every three hours until desired effect is obtained; dose for children, proportion to age.

It will be found to be a safe and mild ca- 110

thartic for constipation, sick-headache, foul breath, heart-burn, dyspepsia and kindred disabilities of the alimentary canal.

I reserve the right to prepare my mentholated or minted cathartic salts in saturated solution form if desired.

Having thus described my improved method of preparing cathartic salts, what I claim and desire to secure by Letters-Patent,

10 is:—
1. The process of making mentholated cathartic salts, consisting of taking equal parts of menthol crystals, oil of peppermint, and oil of spearmint, adding the menthol
15 to approximately one thousand parts of cathartic salts and then triturating the same,

and during such trituration slowly adding, by drops, the oils of peppermint and spearmint until the composition is thoroughly mixed and a perfect blend of mint is distributed throughout the salts.

2. As a composition of matter, a mentholated cathartic salts compounded in the following approximate proportions and consisting of equal parts of menthol crystals, 20 oil of peppermint, and oil of spearmint, to approximately one thousand parts of cathartic salts.

In testimony whereof I have signed my name to this specification.

CHARLES SAMUEL BERRY.
